SLURRY CLASSIFICATION

Johan Sigismund Fasting, Copenhagen, Denmark, assignor to F. L. Smith & Company, New York, N. Y., a corporation of New Jersey

Application May 20, 1938, Serial No. 209,010
In Great Britain May 20, 1937

3 Claims. (Cl. 209—45)

This invention relates to the treatment of slurry for the purpose of separating it into fractions containing particles of different sizes or particles of different materials. More particularly, the invention is concerned with a novel method for effecting slurry classification, and a new apparatus by which the method may be advantageously practiced. The principles of the invention may be employed in the treatment of slurry of various kinds of material or of mixtures thereof, but since the new method and apparatus are especially useful for classifying slurry made of cement raw materials, an application of the invention for that purpose will be illustrated and described by way of example.

In the production of cement according to one method, a slurry of ground raw materials is produced, and separation of such slurry into fractions may be desired for various purposes, as for example, to segregate the coarse and fine particles so that the former may be subjected to a further grinding action. Also, it may be desirable, on occasion, to effect separation of particles which, although of approximately the same size, are of different materials.

In the practice of the invention, the desired classification is accomplished by applying the slurry in a thin layer to the circumferential surface of a rotating body of revolution, such as a cylinder, from which the individual particles are thrown off differentially, and intercepting and separately collecting the particles thrown from the surface of the body at different points in its rotation. The forces to which the particles are subjected during their movement with the rotating body depend upon a number of factors, such as the size and weight of the particles, the nature of the surface of the particles, their chemical composition, the nature of the slurry liquid, etc., and these factors are employed in the new classifying operation. Thus, since the centrifugal force acting on any particle is counteracted by the adhesion of the particle to the liquid present, and as the force is proportional to the weight of the particle, it is apparent that during the rotation of the body, the larger, heavier particles will be thrown from the surface first, and the smaller particles will be retained longer and, in some cases, may have to be removed mechanically. By intercepting and collecting the particles thrown free at different points, a separation by particle size may easily be effected.

If separation is desired of particles of different kinds of material which have about the same average size and nearly the same specific gravity,

one or more substances, such as oil, may be added to the slurry or applied to the body to increase or decrease the adhesion of some of the particles in comparison with the remainder. The particles thrown free in accordance with their varying degrees of adhesion may then be separately intercepted and collected.

For a better understanding of the invention, reference may be had to the accompanying drawing in which the single figure is a view in vertical cross-section of one form of apparatus constructed and operating in accordance with the principles of the invention.

In the apparatus illustrated in the drawing, a cylindrical drum 17 rotating on a horizontal axis is mounted within a housing 18, the bottom 19 of which serves as a container for a quantity of slurry into which the lower surface of the drum continuously dips to pick up a layer. Within the housing, a partition 20 is mounted adjacent that side of the drum moving upward in normal operation, and the partition forms a trough from which leads a discharge chute 21. At the other side of the housing is a partition 22 leading to a discharge chute 23, and having a horizontal edge lying close to the surface of the drum. The bottom of the housing is formed with a neck 24 in which is mounted a suitable agitator 25 which may be driven at a low speed to maintain the slurry in uniform condition, and below the agitator is a valve chamber 26 containing a star valve 27 which controls flow through a discharge 28. Slurry is supplied to the housing through an inlet pipe 29 through which the discharge chute 21 extends.

In the operation of the apparatus shown, particles in the thin layer of slurry picked up on the surface of the drum are thrown off during the rotation of the drum, the larger heavier particles passing upward along the paths indicated by the arrows C to strike the top of the housing and fall back into the trough at the side of the partition 20, from which the particles leave through the chute 21. Lighter particles are thrown from the drum along the paths indicated by the arrows D, striking the top and side walls of the housing and partition 22, so that these particles all pass out of the housing through the chute 23. Heavier, coarser particles, which strike the under side of the trough or fail to leave the drum and pass off through the discharge chutes 21 and 23, return to the body of slurry in the bottom of the housing and settle to the bottom thereof whence they may be removed from time to time through the valve 27.

With the apparatus described, it is possible to exclude from the finer fraction obtained in the apparatus, all particles of a size or specific gravity exceeding a predetermined maximum, and by subjecting the material to successive treatments, it is possible to reduce to a minimum the amount of finer or lighter particles adhering to the coarser, heavier ones, so that an efficient separation into fine and coarse fractions is obtained. Variation of the characteristics of the particles in the fractions obtained is secured by changing the relative position of the rotating body or bodies and the partitions, or by changing the speed of rotation of the body. In the use of the apparatus to obtain separation of particles which are of approximately the same size, but of different materials, a substance is either added to the slurry or applied to the drum, which has the characteristic of varying the adhesion to the drum of the particles of the different materials. A sufficient quantity of such a substance is then used to insure that the particles of one material will be retained longer or thrown off more rapidly than the particles of the other materials, as the case may be, and in this way, classification of the slurry particles may be made according to materials, rather than according to particle size or other physical characteristics.

I claim:

30 1. Apparatus for classifying slurry which comprises a housing containing a body of slurry at the bottom thereof, a drum mounted for rotation within the housing and dipping into the body of slurry, an inlet for introducing slurry 35 into the housing, a partition within the housing receiving particles thrown from the drum in the

first part of the rotation of the latter and intercepted by the housing, an outlet for the particles received on said partition, a second partition within the housing receiving particles thrown from the drum in the later part of the rotation 5 of the drum, an outlet for the particles received on the second partition, and an outlet for particles settling from the body of slurry in the housing.

2. Apparatus for classifying slurry which comprises a housing containing a body of slurry at the bottom thereof, a drum mounted for rotation within the housing and dipping into the body of slurry, an inlet for introducing slurry into the housing, a partition within the housing receiving particles thrown from the drum in the first part of the rotation of the latter and intercepted by the housing, an outlet for the particles received on said partition, a second partition within the housing receiving particles thrown 15 from the drum in the later part of the rotation of the drum, an outlet for the particles received on the second partition, means for agitating the body of slurry, and a valved outlet for particles settling from the body of slurry. 20

3. A method of classifying slurry which comprises applying the slurry in a thin layer to the surface of a body of revolution of cylindrical shape by causing said body to rotate while dipping into a body of the slurry, rotating said body 30 of revolution at such a speed as to cause the particles to be thrown off differentially, intercepting the particles leaving the body and separately collecting the particles thrown from parts of the surface in different angular positions. 35
